UNITED STATES PATENT OFFICE.

GUY R. HELTON, OF ELMER, MISSOURI.

MAIL CATCHING AND DELIVERING DEVICE.

1,072,454.

Specification of Letters Patent.

Patented Sept. 9, 1913.

Application filed October 29, 1912. Serial No. 728,453.

To all whom it may concern:

Be it known that I, GUY R. HELTON, a citizen of the United States, residing at Elmer, in the county of Macon and State of Missouri, have invented new and useful Improvements in Mail Catching and Delivering Devices, of which the following is a specification.

My invention relates to mail catching and delivering devices.

One object of my invention is to provide a hook or equivalent device which is normally projected from a mail car which will engage a mail bag and by such engagement be automatically operated so as to deliver the bag to a point adjacent the car door.

Another object of the invention is to provide means whereby the hook member employed will be closed upon the engagement 20 of a mail bag therewith.

Still another object of the invention is to provide suitable latch mechanism for maintaining the catch member projected which will be operated by a received mail bag to 25 unlatch the member to permit it to move toward the car.

Other objects of the invention reside in the provision of the several novel operating parts hereinafter described taken in connection with drawings accompanying this application, illustrating the preferred embodiment of the invention, and wherein:—

Figure 1 is a plan view partly broken away illustrating my improvements in connection with the side of a car, the parts being in position preparatory to receiving a mail bag. Fig. 2 is a view illustrating the parts in the position after the reception of a mail bag, the mail bag being shown in dotted lines. Fig. 3 is an end view, part of the swinging hook member being broken away for the sake of clearness. Fig. 4 is a cross sectional view on the line 4—4 of Fig. 1. Fig. 5 is a vertical sectional view through 45 the attaching plates employed.

In the several views of the drawings, like reference characters designate like or corresponding parts.

Referring specifically to the drawings, 1 50 designates the side of a car such as a mail car and 2 designates the doorway thereof. To the side of the car is attached in any preferred manner a plate 3 to which is attached a plate 4 preferably by means of a dove tail 55 5 engaging a correspondingly shaped slot in the plate 3, the plate 3 being provided

with a tongue or projection 6 to prevent downward movement of the plate 4 beyond the desired extent. Screws 7 may also be employed to secure the plates 3 and 4 together and to the car. To the plate 4 is suitably attached a bracket 8 provided with angle members 9 and 10. Said member is channeled in cross section as shown and is provided with an opening 11. To the bracket 8 preferably adjacent the center thereof is pivoted on a pin or the like 12, a mail bag receiving member 13, said member having a projected part 14 which extends through and beyond the opening 11 60 and thereat connected to a suitable spring 15, in turn fastened at 16 to the plate 4.

In Fig. 1 the delivering hook member is shown in position ready to receive the mail bag and to maintain this hook member in 75 such position, means preferably as follows is provided. From the portion 10, of bracket 8 projects inwardly through an opening 17 in said hook member 13, a keeper lug 18 having a notch to be engaged by a 80 latch rod 19. The hook member 13 is mostly hollow as shown in the drawings. In said hollow portion are fastened rigidly, disks or guide members 20 through which the latch rod 19 slides and is mounted. Intermediate 85 the guide plates 20 and surrounding the latch rod 19 is a coil spring 21 which bears against a pin 22 on the rod and by such engagement normally maintains the rod in engagement with the keeper 18. The hook 90 proper of the receiving hook member is designated 23 and mounted to operate in the opening thereof is a latch operating lever 24, pivoted to the latch rod at 25 and pivoted to the member 13 at 26.

Means is provided to close the hook member after the reception of a mail bag and such means is preferably as follows: A hook closing arm is provided and designated 27, being pivoted at 28 to the hook 100 member 13. Said arm is connected to a spring 29, in turn connected to the member 13, having a tendency to press the closing arm 27 into closing position. The numeral 30 designates a mail bag engaging hook 105 member which is pivoted at 31 to the member 13. The closing arm 27 is notched at 32 where it is engaged by an arm 33 of the mail bag engaging hook member 30 and normally maintained in open position by 110 such engagement. A leaf spring 34 is fastened to the hook 23 and also to the latch

operating lever 24 and member 30, normally maintaining them in position to be operated by a mail bag. It is to be noticed that the lever 24 is provided with a hook as at 35 which projects forwardly beyond the hook member 30, so that as a mail bag is received, the hook 35 will be acted against before the member 30 is acted against thereby.

In order to return the member 13 to projecting position after the delivery of a mail bag, suitable means is provided which may be as follows: 36 designates an eyelet attached to the member 13, to which eyelet is attached a flexible cord 37 which preferably passes through an eyelet 38 provided on the portion 10 of bracket 8. Said cord 37 preferably leads to the doorway 2 and is preferably fastened at an adjacent point.

In operation the mail bag to be caught is supported from a suitable part so that as the car 1 travels, the mail bag or more specifically a ring or loop thereon will be engaged by the hook 23. Such bag after engagement with the hook 23 will move into engagement with the hook 35, thereby shifting the latch rod 19 and disengaging it from the keeper 18, whereupon the member 13 swings around through the medium of the spring 15 toward the doorway 2. After the engagement with the hook 35, the mail bag moves against the hook member 30, tilting the same and releasing the locking arm 27, which through the medium of its spring 29, moves to locking position, as shown in Fig. 2. It will be seen that the arm 27 effectively closes the hook so as to prevent disengagement of the bag therefrom. It will be seen that the action of the several parts is automatic upon the engagement 40 of a mail bag with the several hooks. It will be stated that the closing arm 27 may be manually returned to the position shown in Fig. 1 and during such movement will automatically engage with the member 30 and automatically be set in open position. Upon the cord 37 being pulled, it is obvious that the hook member 13 will be returned to projecting position and that during movement thereto, the latch rod 19 will engage 50 and automatically lock with the keeper 18, thereby maintaining the member in such position.

From the foregoing, it is thought to be apparent that I have provided an effective device for the purpose stated which will handle the mail bags without injury and a device which will be highly effective in operation, and one which may be manufactured and installed at a small cost.

Changes in the details of construction of course may suggest themselves and such changes, provided they fall within the spirit or scope of the appended claims, are reserved.

Having thus described my said invention,

what I claim as new and desire to secure by Letters Patent is:—

1. In a device of the class described, a bracket, a mail bag receiving member pivoted to said bracket, spring means connected to said member, a keeper on said bracket, a latch rod engaging said keeper, spring means to maintain said rod in engagement with said keeper, a lever pivoted to said rod and to said receiving member, operable through engagement with a mail bag.

2. In a device of the class described, a bracket, a mail bag receiving member pivoted to said bracket, spring means connected to said member, said member having a hollow portion, a keeper on said bracket projecting into said hollow portion, a latch rod engaging said keeper, guide plates in said hollow portion for said latch rod, a spring for said rod mounted intermediate said plates, a lever pivoted to said rod, said lever also pivoted to said receiving member, spring means to maintain said rod in engagement with the keeper, said lever operable through engagement with a mail bag.

3. In a device of the class described, a mail bag receiving member, a closing member, a pivoted member maintaining said closing member open, spring means for said closing member, latch means, an actuating lever for said latch means, said operating lever having a portion projecting beyond the said pivoted member, and both of said latter members operable through engagement with a mail bag.

4. In a device of the character described, a pivotally supported hook shaped mail bag receiving member, spring means for retaining said member in operative position, a locking arm pivotally secured to the said receiving member, spring means to throw the said arm into locking position, a pivoted hook shaped member disposed for engagement with said arm, the said hook shaped member adapted to be actuated through engagement with a mail bag for releasing the locking arm and fastening the mail bag over the said receiving member.

5. A device of the character described including a base plate, a plate member detachably secured to the said base plate, a bracket formed integrally with the said plate member, the said bracket having an extension projecting outwardly from the face thereof, a hook shaped mail bag receiving member pivotally secured to the said bracket, spring means carried by the said plate member adapted to engage the said receiving member for retaining the latter in projected operative position, the movement of the said receiving member being limited in one direction by engagement with the said bracket extension, a locking arm, spring means to throw said arm into locking position, and a pivoted member to maintain said arm in

open position, the said member being actuated through movement of a mail bag.

6. A device of the character described, including a pivotally supported hook shaped mail bag receiving member, spring means to retain said member in projected operative position, a locking arm pivotally secured to the said receiving member, spring means carried by the said receiving member to throw the said arm into locking position, a pivotally supported hook shaped member disposed for engagement with the said locking arm, the said hook shaped member adapted to be actuated through engagement with a mail bag for releasing the said arm and locking the mail bag upon the said receiving member and means for swinging the said receiving member into and out of operative position, as and for the purpose set forth.
- 10 7. In a device of the character described, the combination of a base plate, a plate member detachably secured to the said base plate, a bracket formed integrally with the said plate member, an extension formed in-

tegrally with the said bracket, a mail bag receiving member pivotally secured to the said bracket and disposed for engagement with the said extension, spring means carried by the said plate member to retain the said member in projected position, a keeper carried by the said extension, a latch rod engaging said keeper, spring means to maintain said rod in engagement with said keeper, and a lever pivoted to said rod and to said receiving member, the said lever being operable through engagement with a mail bag, of a locking arm pivotally secured to the said receiving member, spring means to throw the said arm into locking position, and a pivotally supported hook shaped member disposed for engagement with said arm, the said hook shaped member adapted to be actuated through engagement with a mail bag, as and for the purpose set forth.

GUY R. HELTON.
